(57) **CLAIM**

The ornamental design for a display screen or portion thereof with graphical user interface for trajectory creation as shown and described.

DESCRIPTION

FIG. 1 is a front view of a first image of a display screen or portion thereof with graphical user interface for trajectory creation showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof; and,

FIG. 11 is a front view of an eleventh image thereof.

The outermost broken lines in the drawings depict a display screen or portion thereof, or an electronic device having a display screen, and form no part of the claimed design. The broken lines consisting of evenly spaced dash lines in the drawings depict portions of the display screen or portion thereof with graphical user interface for trajectory creation that form no part of the claimed design.

The appearance of the images sequentially transitions between the images shown in FIGS. 1-11. The process or period in which one image transitions to another image forms no part of the claimed design.
